Primary Examiner — S. Bryan Reinholdt, Jr.*Assistant Examiner* — James T Tyree(57) **CLAIM**

The ornamental design for a toy sanitation vehicle, as shown and described.

DESCRIPTION

FIG. 1 is a top, front and right side perspective view of a toy sanitation vehicle, showing my new design; FIG. 2 is a front elevational view thereof; FIG. 3 is a rear elevational view thereof; FIG. 4 is a right side elevational view thereof; FIG. 5 is a left side elevational view thereof; FIG. 6 is a top plan view thereof; and, FIG. 7 is a bottom plan view thereof.

The broken lines show the features of the toy sanitation vehicle that form no part of the claimed design. The dot-dash broken line in FIG. 7 defines the bounds of the claim and forms no part thereof.

1 Claim, 7 Drawing Sheets(56)
